WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed February 19, 1930. Serial No. 429,545.

This invention relates to rock drills, but more particularly to a distributing valve for rock drills of the fluid actuated type.

The objects of the invention are to assure an abundant supply of pressure fluid to the ends of the piston chamber with a minimum lift of the valve, to assure a rapid and positive action of the valve, and to maintain the valve firmly seated in its limiting positions during the time pressure fluid is being admitted into the piston chamber.

Other objects will be in part obvious and in part pointed out hereinafter.

In the accompanying drawings illustrating the invention and in which similar reference characters refer to similar parts,

Figure 1 is a sectional elevation of so much of a rock drill as will serve to illustrate the invention, the valve being shown in position to admit pressure fluid into the rear end of the piston chamber, and

Figure 2 is a similar view showing the valve in position to admit pressure fluid to the front end of the piston chamber.

Referring more particularly to the drawings, A represents a rock drill comprising a cylinder B in which is formed a piston chamber C to receive a reciprocating hammer piston D. The piston chamber C is provided with an exhaust port E which is controlled by the piston D.

Any suitable closure may be provided for the front end of the piston chamber C. For the purpose of illustration a bushing F is shown disposed in the front end of the cylinder and said bushing has a bore G to slidably receive an extension H of the piston D.

In the rear end of the cylinder B is an enlarged bore J for the reception of the valve mechanism which is designated generally by K and also rotation mechanism designated generally by L.

The rotation mechanism L may include the usual ratchet ring O which is bored to receive the head P of a rifle bar Q and has inverted teeth R to act as abutments for spring pressed pawls S of a well known type which are carried by the head P. The rifle bar Q has the usual spiral flutes T to engage the piston D in a well known man-

ner for imparting a rotary movement to the piston. The arrangement is such that the pawls S will engage the teeth R and hold the rifle bar Q stationary during one stroke of the piston D and to permit the rifle bar Q to be rotated during the opposite stroke of the piston.

The valve mechanism K is disposed adjacent the rear end of the piston chamber C and supports the rotation mechanism L. The rotation mechanism L therefore lies near the rear end of the bore J and in this instance the ratchet ring O serves as a seat for a back head U which forms a closure for the rear end of the cylinder B.

The back head U may be secured to the cylinder B in any suitable manner and is provided with a bore V to accommodate a rotary throttle valve W whereby the admission of pressure fluid into the drill may be controlled. Such pressure fluid may be constantly introduced into a chamber X in the throttle valve W, and in the wall of the throttle valve is a port Y which is adapted to register with a supply port Z in the back head U and which port opens into an annular supply reservoir b in the inner face of the back head U.

The valve mechanism K comprises a valve chest e consisting in this instance of a plate d which forms a closure for the rear end of the piston chamber C and said plate has a bore e through which the rifle bar Q extends. A plate f is seated upon the plate d and like the plate d also has a bore e for the reception of the rifle bar Q.

Disposed between the outer portions of the plates f and d is a ring g which forms the outer periphery of an annular valve chamber h, and in the plate d is an annular recess j which forms a portion of the valve chamber and opens into the inner periphery of the valve chamber h. Preferably a plate k is arranged upon the rear end of the plate f to form a seat for the ratchet ring O and for the head P of the rifle bar Q.

Disposed within the valve chamber h is a distributing valve o having a ring shaped portion p which is adapted to reciprocate in the annular valve chamber h. On the inner periphery of the valve o is a lateral flange q

which extends into the annular recess *j* to form therein front and rear pressure chambers *r* and *s* respectively.

The rear surface of the flange *g* constitutes 5 an actuating surface *t* against which pressure fluid may act for actuating the valve and for holding it in its foremost limiting position. Similarly, the front surface of the flange *g* serves as an actuating surface *u* against which 10 pressure fluid may intermittently act to actuate the valve rearwardly and to hold it in its rearmost position.

The pressure fluid utilized for actuating the valve and the piston *D* is conveyed to the valve 15 chamber *h* by a passage *v* which extends through the ratchet ring *O* and the plate *k* and opens into an annular supply chamber *w* in the rear end of the plate *f*.

From the annular supply chamber *w* the 20 pressure fluid flows through a supply passage *x* which extends through the plates *f* and *d* and has branch passages *y* and *z* leading to the rear and front ends respectively of the valve chamber *h*. The outlet openings of the 25 branch passages *y* and *z* are preferably located closely adjacent the pressure chambers *s* and *r* and pressure fluid is admitted into the pressure chambers from the branch passages through grooves 2 and 3 formed in the inner 30 periphery of the valve *o* adjacent the flange *g* and rearwardly and forwardly respectively of said flange.

The rear end of the ring shaped portion *p* of the valve *o* constitutes in this instance a 35 holding surface 4 against which pressure fluid may act to assist that acting against the actuating surface *t* for holding the valve momentarily stationary in the front end of the valve chamber *h*. In like manner, the front 40 end of the ring shaped portion *p* of the valve surface has a holding surface 5 against which pressure fluid acts to assist that acting against the actuating surface *u* for holding the valve stationary in the rear end of the valve chamber *h*.

The holding surfaces 4 and 5 are only intermittently exposed to pressure fluid and such pressure fluid is preferably that which flows to the piston chamber *C* for actuating 50 the piston *D*. The drill is accordingly provided with a front inlet passage or passages 6 which leads from the rear end of the valve chamber *h* to the front end of the piston chamber *C* so that during the course of the 55 pressure fluid from the valve chamber *h* to the front end of the piston chamber *C* such pressure fluid will act against the holding surface 4 to hold the valve forwardly. The pressure fluid utilized for actuating the piston *D* forwardly on its working stroke is 60 conveyed into the front end of the piston chamber *C* by a rear inlet passage 7 which extends from the front end of the valve chamber *h* to the rear end of the piston chamber *C*. The drill may be provided with a 65

plurality of passages 6 and 7 for conveying the pressure fluid to the ends of the piston chamber but, for convenience of illustration, only one of each of these passages are shown.

In order to provide an escape for the pressure fluid acting against the actuating surfaces *t* and *u* the respective pressure chambers wherein said actuating surfaces lie are provided with exhaust passages 8 and 9 which open into the piston chamber *C* and are controlled by the piston *D*. The exhaust passage 9 leads in this instance from the pressure chamber *r* and opens into the piston chamber *C* at a point immediately rearwardly of the exhaust port *E* and the exhaust passage 8 leads from the pressure chamber *s* to the front end of the piston chamber *C* into which it opens at a point adjacent the exhaust port *E*.

The following is a description of the operation of the device: With the valve *o* in its rearmost position, as illustrated in Figure 1, pressure fluid will flow through the passages leading from the throttle valve to the annular supply chamber, thence through 80 the passage *x* and its branch passages *y* and *z*.

The pressure fluid flowing through the passage *z* passes over the holding surface 5 against which it acts to assist in holding the valve *o* rearwardly and flows through the inlet passage 7 into the rear end of the piston chamber *C* to drive the piston *D* forwardly. During the time the piston is moving forwardly and until slightly prior to the uncovering of the exhaust port *E* the exhaust passage 9 will also be covered by the piston so that the pressure fluid previously admitted into the pressure chamber *r* will be entrapped therein to maintain the valve *o* stationary in its rearmost position.

At the same time pressure fluid will flow from the branch passage *y* through the groove 2 into the pressure chamber *s* to act against the actuating surface *t*. Inasmuch however, that the combined areas of the actuating surface *u* and the holding surface 5 exceed the area of the actuating surface *t* the valve will remain momentarily stationary.

As the piston *D* proceeds forwardly it will 115 first uncover the exhaust passage 9 and immediately thereafter the exhaust port *E*. The pressure fluid in the rear end of the piston chamber *C* will then exhaust to the atmosphere as will also that in the pressure chamber *r*. The pressure fluid in the pressure chamber *s* will then act to throw the valve *o* forwardly, thus cutting off the supply of pressure fluid to the rear end of the piston chamber and establishing communication 120 between the branch passage *y* and the front inlet passage 6.

In the new position of the valve pressure fluid flows into the front end of the piston chamber to drive the piston *D* rearwardly 130

to its initial position. During the admission of pressure fluid to the front end of the piston chamber the pressure fluid within the pressure chamber *s* will be entrapped there-
 5 in by the piston *D* which will then overlie the exhaust passage *8* throughout a considerable portion of its stroke and the pressure fluid flowing over the holding surface *4* will also assist in holding the valve *o* for-
 10 wardly.

Proceeding rearwardly the piston will uncover the exhaust passage *8* and the exhaust port *E* so that the pressure fluid in the front end of the piston chamber *C* and the pressure fluid in the pressure chamber *s* may be exhausted to the atmosphere. The valve *o* will then be shifted to its rearmost position by the pressure fluid admitted into the pressure chamber *r* by the groove *3* during the 20 time the valve *o* occupied its foremost position.

As may be readily observed the valve constructed in the manner described affords a wide area over which pressure fluid flows to the inlet passages and requires only a minimum lift of the valve. These advantages are made possible by the large diameter of the valve which this form of construction permits. Due to the small distance which the 30 valve is required to travel it will impact only lightly against its seats and will therefore be protected against the severe jars and shocks which are usually responsible for valve breakage.

35 I claim:

1. In a fluid actuated rock drill, the combination of a cylinder having a piston chamber and a reciprocating piston in the piston chamber, an exhaust port in the cylinder, a 40 valve chest having a valve chamber and comprising an annular recess, inlet passages leading from the valve chamber to the piston chamber, a ring valve reciprocable in the valve chamber to control the inlet passages and encircling the annular recess, a flange on the inner surface of the valve dividing the annular recess into a pair of pressure chambers, opposed actuating surfaces on the flange, grooves on the inner surfaces of the valve to 45 convey pressure fluid directly from supply into the pressure chambers for actuating and holding the valve, holding surfaces on the valve against which pressure fluid flowing to the inlet passages acts to assist in holding the valve, and piston controlled passages leading from the pressure chambers to the piston chamber for exhausting the pressure fluid from the said pressure chambers.

55 2. In a fluid actuated rock drill, the combination of a cylinder having a piston chamber and a reciprocating piston in the piston chamber, an exhaust port in the cylinder, a valve chest having an annular valve chamber and comprising an annular recess intermediate the ends of the valve chamber, inlet pas-

sages leading from the ends of the valve chamber to the piston chamber, a valve in the valve chamber encircling the annular recess and having an internal flange to divide the annular recess into a pair of pressure 70 chambers, opposed actuating surfaces on the flange, grooves on the inner surface of the valve to intermittently convey pressure fluid from supply into the pressure chambers for actuating and holding the valve, holding surfaces on the valve against which pressure fluid flowing to the inlet passages acts to assist in holding the valve, and piston controlled passages leading from the pressure chambers to the valve chamber for exhausting 80 pressure fluid from the said pressure chambers.

3. In a fluid actuated rock drill, the combination of a cylinder having a piston chamber and a piston in the piston chamber, an 85 exhaust port in the cylinder, a valve chest having an annular valve chamber and comprising an annular recess opening into the inner periphery of the valve chamber, inlet passages leading from the ends of the valve 90 chamber to the piston chamber, a valve in the valve chamber having a flange extending into the recess to form a pair of pressure chambers therein, opposed actuating surfaces on the flange, grooves in the valve to intermittently admit pressure fluid into the pressure 95 chambers for actuating and holding the valve, holding surfaces on the ends of the valve of smaller area than the actuating surfaces and being exposed to the pressure fluid 100 flowing to the inlet passages for holding the valve, and passages leading from the pressure chambers to the piston chamber and being controlled by the piston for exhausting 105 pressure fluid from the pressure chambers.

In testimony whereof I have signed this specification.
